UNITED STATES PATENT OFFICE.

CHARLES D. MOSHER, OF NEW YORK, N. Y.

OIL-BURNING APPARATUS.

1,420,208.

Specification of Letters Patent. Patented June 20, 1922.

Application filed June 19, 1918, Serial No. 240,732. Renewed April 8, 1922. Serial No. 550,792.

To all whom it may concern:

Be it known that I, CHARLES D. MOSHER, a citizen of the United States, residing at New York city, in the county of New York and

5 State of New York, have invented certain new and useful Improvements in Oil-Burning Apparatus, of which the following is a specification, reference being had therein to the accompanying drawing.

10 My invention relates to improvements in gasifying and atomizing fuel and has particular reference to an apparatus for pre-heating a liquid fuel such as hydrocarbon oil and then atomizing the same by means of the 15 oil vapors or gas which are preferably created by the use of steam coils in the oil and gas chambers.

15 In the accompanying drawings, I have illustrated in Fig. 1 in side elevation, a suitable form of apparatus embodying an application of my invention. Fig. 2 is a vertical cross-section showing the interior arrangement of the apparatus shown in Fig. 1. Fig. 20 3 is a plan view looking down upon Fig. 1. Fig. 4 is a plan view looking down upon Fig. 5. Fig. 5 is a cross-section on the line 25 5—5 of Fig. 4. Fig. 6 is a cross-section on the line 6—6 of Fig. 2, and Fig. 7 is a plan view looking down upon Fig. 2 with the 30 upper parts removed.

35 8 is a suitable form of tank separated by a perforated diaphragm 9 separating the upper and lower chambers 10 and 11 respectively. The lower chamber is vertically divided into four sections as indicated in Fig. 4 by the reference characters 12 to 15 inclusive, this division being provided for by the partitions 16—17, the partition 17 being cut away at the bottom as indicated at 18 in 40 Figs. 2 and 5.

45 Referring now to Figs. 1 and 2 it will be seen that the oil inlet is indicated at 19 from which point it is drawn up to the pumps 20—21 subject to control valve 20'—21' and these pumps are steam driven to feed the oil 50 through the inlets 22—23 into the several compartments 12 to 15 inclusive where it rises passing through the cut-away portion 18 and over the partitions 16—17 until it reaches the predetermined height 24 at 55 which point the ball valve 25 being lifted operates the cut-off valve 26 which stops the further feed of oil maintaining the same at a level slightly above the tops of the partitions 16—17 and slightly below the screen 9.

The steam inlet is indicated at 27 where

the steam, preferably superheated, passes through a regulating valve 46 for controlling the pressure or temperature of the heating medium for generating gas from the 60 oil in the lower chamber, the steam passing downwardly through the coils 28 and again through the coil 29 returning by the tube 30 to the circular chamber 31 connecting with the steam outlet 32. The steam inlet 27 being in communication with the chamber 33 also feeds the coils 34 communicating therewith which said coils also supply the coils 35 in the lower chamber 11, which said coils have a return to the steam outlet 32 by the 70 tubes 36 also communicating with the chamber 31. 37 indicates a suitable steam gauge for reading the pressure.

38 indicates the oil outlet, and 39 the vapor or gas outlet controlled by the valve 47. 75 Also from the steam inlet 27 it will be observed that there is a pipe 41 which supplies the steam pipes 42—43 which in turn feed the pumps 44—45 for supplying the oil to the apparatus, and 46 indicates a suitable 80 valve in the steam supply circuit for controlling the pressure and temperature of steam entering the coils.

85 From the foregoing it will be seen that the oil vaporized in the lower chamber 11 by the coils 29—35 escapes from the outlet 39, in the form of vapor or gas while at the same time liquid fuel may be drawn off from the outlet 38 through a reducing valve 38' and stop valve 48 to the burner 49, the former 90 controlled by the valve 47 and the latter by the valve 48, thus facilitating a proper adjustment of quality of the mixture which may be atomized from the nozzle 49.

95 It is well known that fuel oil when subjected to temperatures sufficiently high to boil off the vapor or gas, forms numerous bubbles which it is desired to break up by providing the perforated diaphragm 9 so that the gas bubbles are broken up in passing through the small perforations in the plate allowing only the gas to pass into the upper chamber, the gas in the upper chamber being more effectually superheated by the steam coils in a separate chamber than it 100 could be if it were in the same chamber with the liquid.

105 Of course it will be understood that various modifications may be made in the construction and arrangement of parts without departing from the spirit of the invention as claimed.

I claim:—

1. In an apparatus of the class described, a vertical cylindrical tank divided by vertical baffling plates, means for maintaining a predetermined level of fuel oil therein, a perforated plate transversely across said tank, heating a group of coils above and another group of heating coils below said plate and directly connected, an inlet for a heating medium at the top of said upper coils, an outlet for said heating medium connected at the bottom of said lower coils, and an oil and vapor outlet below and above said oil.
2. In an apparatus of the class described, a vertical cylindrical tank divided by vertical baffling plates, means for maintaining a predetermined level of fuel oil therein, a perforated plate transversely across said tank, heating a group of coils above and another group of heating coils below said plate and directly connected, an inlet for a heating medium at the top of said upper coils, an outlet for said heating medium connected at the bottom of said lower coils, an oil and vapor outlet below and above said oil, respectively and a reducing valve between said tank and said oil outlet.
3. In an apparatus of the class described, a cylindrical chamber having a perforated member dividing the upper and lower portions thereof, separate groups of heating tubes in each of said portions of said tank, compartments in the lower of said tank portions and communication therebetween, and means for taking off liquid and vaporous portions of said oil together.
4. In an apparatus of the class described, a cylindrical chamber having a perforated member dividing the upper and lower portions thereof, separate groups of heating tubes in each of said portions of said tank, compartments in the lower of said tank portions and communication therebetween, means for taking off liquid and vaporous portions of said oil together, and means in combination with said tubes for circulating a heating medium therethrough.
5. In an apparatus of the class described, a cylindrical chamber having a perforated member dividing the upper and lower portions thereof, separate connected groups of heating tubes in each of said portions of said tank, compartments in the lower of said tank portions and communication therebetween, means for taking off liquid and vaporous portions of said oil together, means in combination with said tubes for circulating a heating medium therethrough, an oil outlet and a pressure controlling valve therein, and an atomizer at said oil outlet for atomizing said oil.
6. In an apparatus of the class described, an oil tank and means for maintaining a predetermined level of oil therein, separate heating coils in the upper and groups of separate coils in the lower portions of said tank for vaporizing said oil, means for controlling the outlet of said oil, an atomizer at said outlet for atomizing the same, said atomizer in communication with the vapor generated from said oil in said tank.
7. In an apparatus of the class described, an oil tank and means for maintaining a predetermined level of oil therein, separate heating coils in the upper and groups of separate coils in the lower portions of said tank for vaporizing said oil, means for controlling the outlet of said oil, an atomizer at said outlet for atomizing the same, said atomizer in communication with the vapor generated from said oil in said tank, said upper and lower portions of said tank separated by a partition.
8. In an apparatus of the class described, an oil tank and means for maintaining a predetermined level of oil therein, separate heating coils in the upper and groups of separate coils in the lower portions of said tank for vaporizing said oil, means for controlling the outlet of said oil, an atomizer at said outlet for atomizing the same, said atomizer in communication with the vapor generator from said oil in said tank, said lower portion of said tank provided with baffle partitions for insuring the circulation of said oil.
9. In an apparatus of the class described, a vertical cylindrical tank horizontally divided by a baffle plate, means for maintaining a predetermined level of fuel beneath said plate, coils above and below said plate and directly connected, an inlet for a heating medium at the top of said upper coils and an outlet for said heating medium connected at the bottom of the lower of said coils, a liquid fuel and a vapor fuel outlet adjacently situated, and a reducing valve in said fuel circuit.

In testimony whereof I hereunto affix my signature in the presence of two witnesses.

CHARLES D. MOSHER.
